HEAT EXCHANGE APPARATUS

John P. Rathbun, Prospect Park, Pa., assignor to
Westinghouse Electric Corporation, East Pitts-
burgh, Pa., a corporation of Pennsylvania

Application April 13, 1944, Serial No. 530,821

2 Claims. (Cl. 257—32)

1

This invention relates to heat exchange apparatus, more particularly to partition structure therein, and has for an object the provision of improved sealing means between such partition structure and the shell of the heat exchange apparatus.

Another object of the invention is to provide, in heat exchange apparatus of the vertical type, means for liquid sealing vertical joints therein.

Yet another object of the invention is to provide, in heat exchange apparatus of the vertical type, vertical partition structure segregating a portion of the space within the shell from the remaining portion thereof, together with novel sealing means at the vertical edges of the partition structure where they abut or closely approach the shell structure.

A further object of the invention is to provide, in heat exchange apparatus of the vertical type, vertical partition structure having channel-shaped vertical edges disposed in contiguous relation to the shell side wall, together with means for maintaining the spaces between the legs of the channel-shaped edges flooded with condensate to prevent leakage of steam or other gases to the segregated space from the remaining space.

These and other objects are effected by the invention as will be apparent from the following description and claims taken in connection with the accompanying drawings, forming a part of this application, in which:

Fig. 1 is a vertical sectional view taken along the line I—I of Fig. 3, looking in the direction indicated by the arrows:

Fig. 2 is a sectional view taken along the line II—II of Fig. 1, looking in the direction indicated by the arrows;

Fig. 3 is a transverse sectional view taken along the line III—III of Fig. 1, looking in the direction indicated by the arrows;

Fig. 4 is an enlarged fragmentary sectional view taken along the line IV—IV of Fig. 1, looking in the direction indicated by the arrows;

Fig. 5 is an enlarged fragmentary perspective view of the upper end of the bifurcated sealing members illustrated generally in Figs. 3 and 4, with the flexible sealing members 35 omitted for the sake of clearness; and,

Fig. 6 is an enlarged fragmentary sectional view of the sealing structure shown generally at the upper left of Fig. 1.

Referring now to the drawings more in detail, there is shown a heat exchanger, indicated in its entirety by the reference character 10, comprising a vertically-disposed shell 11 having a

steam inlet 12 and a condensate outlet 13. A plurality of U-tubes 14 extend longitudinally of the shell and have their terminal portions supported by the tube plate 15. This tube plate constitutes a portion of the water box structure 16 which is divided by partitions 17 and 18 into an inlet chamber 19, a reversing chamber 20 and a discharge chamber 21, this water box construction providing for flow of water through the tubes in four passes. The inlet and discharge chambers 19 and 21 are provided with the usual supply and discharge connections 22 and 23, respectively.

In order to provide a subcooling section 25, the space surrounding the tubes of the first water pass is segregated from the remaining space within the shell 11 by a vertical partition structure 26, comprising radially-extending portions 27 and 28 joined by a cross-corner portion 29. In order that the tube bundle may be removable as a unit, it is necessary that the partition structure 26 likewise be removable with the tube bundle, this necessitating a removable seal between the outer edges of the radially-extending partition sections 27 and 28 and the shell 11. This novel sealing means, constituting the subject matter of the present invention, is indicated in its entirety by the reference character 30 and comprises a U-shaped member having a base portion 31 carrying a pair of legs 32 and 33, terminating in close proximity to the shell 11, as at 34.

Preferably, each of these legs has secured at its inner surface a plurality of flexible laminations 35, of the type more fully disclosed in United States Letters Patent Nos. 1,803,034 and 1,803,035, granted to Westinghouse Electric & Manufacturing Company on April 28, 1931. Inasmuch as this specific type of seal is well-known in the trade, being sold under the name "Lamiflex," further description thereof in the present case is believed unnecessary. However, it may be pointed out that these flexible laminations 35 may be secured to the legs 32 and 33 in any suitable manner, as by spot-welding and/or the use of the plates 36 and 37 together with the welding 38, illustrated in Fig. 4. The base portion 31 of the U-member is preferably secured to the outer edges of the radially-extending partition sections 27 and 28 by welding, at 40.

A horizontal partition 42 is disposed between the radially-extending vertical partition sections 27 and 28 and the shell wall which cooperates therewith, to form a top closure for the subcooling section 25. While in the construction herein illustrated, this subcooling section 25 extends

substantially the full length of the first water pass, it will be apparent that the same may be of any lesser length or extent, with the vertical partition structure 26 being correspondingly shorter. The horizontal partition 42 is preferably welded, or otherwise secured to the vertical partition structure 26 and is sealed with respect to the adjacent portion of the shell 11 by an angular packing member 43 and clamping ring 44 (Fig. 6).

As indicated in Fig. 1, the horizontal partition 42 is disposed a short distance below the upper edge of the vertical baffle structure 26, the upper edge of the latter which projects above the horizontal partition 42 serving as a dam to retain upon the latter condensate either falling thereon from the tubes thereabove or flashed thereonto through the inlet connection 46 from an external source such as another heat exchanger operating at higher pressures.

The body of condensate collecting upon the horizontal partition 42 serves to water-seal the joints about the partition and the tubes and prevent any possible leakage of steam therepast to the subcooling section 25.

As indicated in Figs. 1 and 5, the inner leg of each U-shaped member (33 in Figs. 3 and 4) is shorter than the other leg and the vertical partition structure 26, with the result that excess condensate deposited upon the horizontal partition 42 flows over the upper edge of the shorter leg 33 into the space 48 between the two legs 32 and 33. Under operating conditions where condensate is flashed into the shell through the inlet 46 from an external source, or where the subcooling section 25 is of materially lesser length than the length of the tube bundle passing therethrough, sufficient condensate will be deposited on the horizontal baffle 42 to maintain the same covered and also to maintain the spaces 48 at the outer edges of the vertical baffle structure 26 filled, thereby sealing the subcooling section against leakage of steam thereinto from the steam space constituting the remaining portion of the shell interior.

It is believed that operation of the heat exchange apparatus as a whole will be obvious to those skilled in the art; however, it may be stated that steam, entering the inlet connection 12, passes around the impingement baffle 50 and follows a convoluted or criss-cross path from that point downwardly to the bottom of the shell, flowing back and forth between the successive baffles 51 and 52, which are disposed with opposite edges in spaced relation to the adjacent sections 27 and 28 of the vertical partition structure. In other words, the alternate baffles 51 and 52 are constructed and arranged to provide openings 53 and 54, respectively, at opposite ends thereof for staggered flow of steam from top to bottom of the shell. In order to prevent bypassing of steam through the untubed central portion of the shell, this portion is closed off by partition members 56 and 57, cooperating with the cross-corner portion 29 of the vertical partition structure 26. However, the partition 57 is provided, near the bottom of the shell, with an opening 58 for flow of condensate into the central portion of the shell for flow therefrom through the passage 59 and conduit 60 to the upper portion of the subcooling section 25.

The condensate outlet 13 is located in the subcooling section adjacent the bottom thereof, and is provided with a discharge valve 61, controlled through linkage 62 and 63 by the float 64, con-

tained in the float housing 65. Inasmuch as the latter is in communication with the steam space 66 at the lower portion of the shell by means of the conduit 67, and with the condensate conduit 5 60 through the conduit 68, the level of condensate in the float housing 65 corresponds to the condensate level in the heat exchanger. It will be obvious that, upon an increase in the condensate level within the heat exchanger, the float 10 will be raised, resulting in opening of the condensate discharge valve 61, thereby permitting the pressure existing within the heat exchanger to force the condensate from the latter through the passage 59 and conduit 60 into the upper end 15 of the subcooling section 25, at the same time forcing out at the bottom of the subcooling section a corresponding amount of condensate, until the level of condensate in the heat exchanger has fallen sufficiently to move the float into 20 valve-closing position.

The sub-cooling section 25 is provided with alternating baffles 70 and 71 having openings 72 and 73 at opposite ends for producing maximum flow path conditions in the subcooling section, 25 similar to those in the condensing portion of the apparatus.

The upper end of the shell may be provided with the usual vent 76 and the subcooling section 25 likewise provided with an air vent 77 in order 30 that the latter may be maintained flooded with condensate at all times during normal operation of the apparatus.

While the invention has been shown in but one form, it will be obvious to those skilled in the art that it is not so limited, but is susceptible of various changes and modifications without departing from the spirit thereof.

What is claimed is:

1. Heat exchange apparatus comprising a vertical shell having a steam inlet and a condensate outlet, a removable bundle of tubes disposed vertically in said shell, water box structure associated with the terminal portions of the tubes and providing for circulation of water there- 10 through, vertical partition structure removable from the shell with the tube bundle and cooperating with the shell to segregate a portion of the space about the tubes from the remaining space within the shell, bifurcated vertical edges on the partition structure providing vertical channels opening toward the cooperating shell, resilient sealing members carried by the branches of the bifurcations and frictionally contacting the contiguous shell, a source of condensate comprising upper portions of the tubes which extend through the segregated portion of space and thereabove, and a pan-like structure positioned beneath said source of condensate for reception of condensate therefrom and discharge of condensate to the vertical channels to maintain them flooded.

2. Heat exchange apparatus comprising a vertical shell having a steam inlet and a condensate outlet, a removable bundle of tubes disposed vertically in said shell, water box structure associated with the terminal portions of the tubes and providing for circulation of water there- 65 through, vertical partition structure removable from the shell with the tube bundle and cooperating with the shell to segregate a portion of the space about the tubes from the remaining space within the shell, bifurcated vertical edges on the partition structure providing vertical channels opening toward the cooperating shell, resilient sealing members carried by the branches of the 70

bifurcations and frictionally contacting the contiguous shell, a source of condensate comprising upper portions of the tubes which extend through the segregated portion of space and thereabove, a horizontal baffle positioned directly beneath said source to receive condensate therefrom, and means providing a dam extending above the edges of said horizontal baffle, said means including a branch of each bifurcation and the portions of said dam defined by said bifurcation branches being lower than the remaining portions of said dam, whereby condensate collecting on said horizontal baffle overflows into the vertical channels to maintain them flooded with condensate.
